PORTABLE EXERCISER

Ernest Richie Davidson, Braintree, Mass.

Application March 13, 1953, Serial No. 342,187

4 Claims. (Cl. 273—97)

This invention relates to a portable exerciser and has as its object to provide a new and amusing combination of well-known parts for the purpose of constructing a device which will exercise people, and particularly people who are over-weight, and more particularly people who are over-weight at the waist-line; by causing such people to bend up and down successively in the operation of the device.

Again, the new construction provided herein may be used as a toy for a child, or as an amusement device for adults at a party, fair or other social function; or, from a more serious point of view, as an exerciser for those hundreds of people who are trying to regain the use of their limbs as an aftermath of an attack of the dreaded polio disease.

Another object of this invention is to provide an exerciser, having a new combination of parts, which is exceedingly inexpensive to construct, which is without danger to the user and which will hold the attention of the user for many days as he attempts to build up skill in the operation of the exerciser.

In the accompanying drawing, Fig. 1 is a side elevation view of my exerciser, showing an elongated body or stick in an inclined position and having a curve at its lower extremity. A groove is on the upper face of the stick and is adapted to guide a ball down the incline of the stick. By co-ordinated movement of the body and arm, the ball may be caught in a pocket at the top of the stick and be made to move in a continuous cycle.

Fig. 2 is an enlarged view of a trigger mechanism adapted to hold or release the said ball from the said pocket.

Figure 3 is a front view of the trigger.

Fig. 4 is a plan view of the stick in the inclined position.

Fig. 5 is an enlarged view of the top of the pocket showing securing of the pocket to the stick by means of sliding friction; and securing of a ball with an elastic cord to the said stick.

Now, referring again to Fig. 1, is shown a portable, elongated body or stick 1 made preferably of wood, and having means to guide a ball down the entire length of the stick when the said stick is held in an inclined position, the said means comprising preferably a groove 2 in the upper surface of the said stick. Further is shown the said stick curved at its lower extremity to form a substantially semi-circle 3 having the said groove on the inside.

Further is shown a curved handle 4 at the top of the said stick, and a hand H holding the stick, showing the entire exerciser to be portable.

Moreover is shown a pocket adapted to catch a ball, the said pocket 5 being secured by friction to the upper portion of the said stick and being adapted to slide to predetermined positions up and down the said stick and to be held at such predetermined positions by friction, as is shown at one position of the said pocket shown in dotted lines at 5A. The said pocket 5 is made preferably of tin-plate and in the form of a hollow cone having

2

its wider end uppermost. The axis of the said pocket 5 is oblique to the main axis of the stick 1 by substantially five to ten degrees to permit not only continuous circuit of the ball, but very rapid circuit of the ball. Moreover, 5 a slit 5B runs at the front of the pocket from the top to the bottom to allow the passage of an elastic cord which secures a ball to the said stick.

Again in Fig. 1 is shown a ball 9 made preferably of rubber and secured to the said stick 1 by means of a cord 10, the said cord being made preferably of elastic rubber. A hole 1B is adapted to pass the said cord 10 through the said stick 1, and a knot 10A in the cord secures the cord from pulling out of the stick. The cord is of sufficient length to allow the ball to roll to the bottom of the stick and to rise above the uppermost position of the pocket.

Further in Fig. 1 is shown a combination ball-stop and trigger 8 adapted to be moved by a finger from a stopping position as shown, to a non-stopping position 20 as shown in dotted lines in Fig. 2.

Fig. 2 is an enlarged side view of the combination ball-stop and trigger; and in which view is shown the stick 1, the groove 2 and the ball 9 in the groove. Moreover is shown the trigger and ball-stop 8 in position to stop 25 the ball 9 from running down the incline of the stick. Again is shown a pin 8A upon which the combination ball-stop and trigger turn to the non-stop position. A slot 1A in the bottom side of the stick is adapted to receive the ball-stop and trigger combination at the full non-stop position.

Fig. 3 is a front view of the ball-stop and trigger combination; and in which view is shown the stick 1, a slot 1A in the bottom of the stick adapted to receive the ball-stop and trigger combination 8, and the pin 8A upon which the latter turns.

Fig. 4 is a plan view of the stick in the inclined position; and in which figure is shown the stick 1, the groove 2, the curve 3 at the bottom of the stick and the handle 4.

Fig. 5 is an enlarged sectional view on a horizontal line at the top of the pocket; and in which figure is shown the stick 1 and the groove 2, and is shown the pocket 5 made preferably of one piece of tin-plate and conforming in a friction fit around the back of the said stick, the said friction fit of the pocket being adapted to allow the pocket to slide up and down the stick and to remain at any predetermined position on the stick. Again is shown the rubber ball 9 secured to the stick by means of an elastic cord 10. A hole 1B in the back of the stick is adapted to pass the free end of the elastic cord, and a knot 10A in the cord prevents the cord from pulling out of the stick. Now again is shown a slit 5B in the front of the pocket, the said slit being adapted to pass the elastic cord when the ball rolls down through the pocket.

Referring now to Fig. 1, my exerciser is adapted to use either a free ball or an attached ball. Thus, my portable exerciser is grasped at the handle 4 by the hand of the user H and held in an inclined position as shown, the bottom of the exerciser being free above the floor-line E—F. Both the free ball and the attached ball may be made to pass through the same cycles in the exerciser, with the difference being that the attached ball requires more skill to maneuver due to the retracting force of the elastic cord.

In the elementary phase of the movement of the exerciser, the free ball is first placed in the pocket at the low position 5A on the stick. The ball is allowed to pass through this pocket with a slight retarding action at the bottom of the said cone-shaped pocket. The ball now rolls to the bottom of the stick and is returned upward by the curve 3. At this point, an additional force must be imparted to the ball by a backward movement

of the trunk, waist and arm of the user in order to lift the ball up to and higher than the pocket 5A. The trunk, waist and arm of the user must now be brought forward in a co-ordinated movement to catch and engage the ball in the said pocket. Thus the ball is made to move in a continuous cycle as shown by the dotted line and balls 7C—7B. This cycle of the ball is not accomplished easily, and requires effort and co-ordination of the movements of the body of the user.

As skill is acquired, the pocket 5A is moved higher up on the stick with subsequent enlargement of the cycle of the ball and greater effort on the part of the user. The maximum cycle of the free ball reaching the course is indicated by the dotted line and balls 7—7A—7B—7D.

In employing my exerciser with the attached ball using the elastic cord, a higher degree of skill is required and greater effort in flexing the body is required in order to meet the retracting force of the elastic cord. Thus, referring again to Fig. 1, a brake in the form of a simple ball-stop and trigger combination is needed and is shown at 8. Obviously the combination ball-stop and trigger may be used with both the free ball and the attached ball.

In employing the attached ball, the ball is first placed in the pocket at the low position 5A and allowed to run down the stick; the elastic cord passing through the slit in the front of the pocket. This low position of the pocket allows some judgement of the retracting force of the elastic cord. The pocket is raised step by step until it reaches a high position as indicated at 5. At this position the ball must be braked by the combination ball-stop and trigger 8 as the ball builds up speed in traveling the cycle 7A—7B—7D—9, or larger cycles (not shown).

I have found in using my exerciser that the elastic cord does not become tangled with the ball, as the ball presents an all-rounded surface which evades the cord. Again, I have found that the cord passes easily through the slit in front of the pocket, and usually immediately after the ball passes through the pocket.

My exerciser weighs about one pound and requires little or no effort to hold. Again, I have found that my exerciser fascinates and holds the attention of the user for weeks and weeks, and that its use by an ordinarily well person for a period of ten to fifteen minutes each day results in a feeling of physical well-being.

I have found that my exerciser is inexpensive to make, is quite strong and will stand considerable usage; moreover, in the event of breakage, a replacement part is quite inexpensive and very easy to assemble.

I am aware that certain devices having a rubber ball and a securing elastic cord have been known for a long time; I am not concerned with these.

I am aware that certain devices employing the principle of an inclined plane and a moving body thereon have been known for a long time; I am therefore not concerned with these.

I claim:

1. A portable exerciser comprising an elongated body member having a straight track along which a ball is adapted to roll freely, a handle extending laterally at an obtuse angle from the upper end of said body member, a curved end member extending from the lower end of said body member and curving upwardly therefrom at the side opposite the handle, said end member having at its inner face a curved extension of said track, a ball secured to said body member by a cord, and a pocket

open at the top and bottom frictionally engaging said body member and adjustable in position from one end of said body member to the other to receive said ball through its upper end and guide it onto said track, said pocket having a slot sufficiently wide to pass said cord extending from end to end of the wall of said pocket opposite said track.

2. A portable exerciser comprising an elongated body member having a straight track along which a ball is adapted to roll freely, a handle extending laterally at an obtuse angle from the upper end thereof, a curved end member extending from the lower end of said body member and curving upwardly therefrom at the side opposite the handle, said end member having at its inner face an extension of said track curving through approximately 180°, a ball secured to said body member by an elastic cord, a pocket open at top and bottom to receive said ball and guide it onto said track, said pocket having a slot sufficiently wide to pass said cord extending from end to end of the wall of said pocket opposite said track, and means for releasably clamping said pocket to said body member adjacent said track.

3. A portable exerciser comprising a J-shaped guide member having along its inner face a track along which a ball is adapted to roll freely, a handle extending laterally from the end of the longer leg of the guide member at the side opposite the shorter leg, a pocket open at both ends and tapering in diameter from the upper end toward the lower end and adapted to receive said ball through its upper end and guide it onto said track through its lower end, means for releasably clamping said pocket to the longer leg of said guide member adjacent said track, said pocket and clamping means comprising a member of flexible sheet material frictionally engaging said guide member at opposing sides thereof laterally of said track and extending arcuately across said track in spaced relation thereto.

4. A portable exerciser comprising a J-shaped guide member having along its inner face a track along which a ball is adapted to roll freely, a handle extending laterally from the end of the longer leg of the guide member at the side opposite the shorter leg, a pocket open at both ends and tapering in diameter from the upper end toward the lower end and adapted to receive said ball through its upper end and guide it onto said track through its lower end, means for releasably clamping said pocket to the longer leg of said guide member adjacent said track, said pocket and clamping means comprising a single piece of flexible sheet material having a rear wall slidably engaging the face of said guide member opposite the track and a pair of arms extending from opposite ends of said rear wall in frictional engagement with opposite sides of said guide member, said arms having arcuate end portions terminating adjacent each other.
